UNITED STATES PATENT OFFICE

146,539

DESIGN FOR A SEWING MACHINE

Fritz Gegauf, Steckborn, Switzerland, assignor to
Fritz Gegauf's Sonne Aktiengesellschaft, Steck-
born, Switzerland

Application February 26, 1946, Serial No. 126,940
In Switzerland October 5, 1945

Term of patent 14 years

(Cl. D70—1)

To all whom it may concern:

Be it known that Fritz Gegauf, a citizen of the Republic of Switzerland, and resident of Steckborn, Canton of Thurgau, Switzerland, has invented a new, original, and ornamental Design for a Sewing Machine, of which the following is a specification, reference being had to the accompanying drawing, forming part thereof, in which

Fig. 1 is a perspective view of a sewing machine embodying my new design;

Fig. 2 is a left-hand side elevational view thereof;

Fig. 3 is a right-hand side elevational view thereof; and

Fig. 4 is a rear view thereof.

I claim:

The ornamental design for a sewing machine, substantially as shown.

FRITZ GEGAUF.

Certificate of Correction

Design No. 146,539.

April 1, 1947.

FRITZ GEGAUF

It is hereby certified that the name of the assignee in the above numbered patent was erroneously described and specified as "Fritz Gegauf's Sonne Aktiengesellschaft" whereas said name should have been described and specified as *Fritz Gegauf's Sohne Aktiengesellschaft*, as shown by the record of assignments in this Office; and that the said Letters Patent should be read with this correction therein that the same may conform to the record of the case in the Patent Office.

Signed and sealed this 17th day of June, A. D. 1947.

[SEAL]

LESLIE FRAZER,

First Assistant Commissioner of Patents.
